Primary Examiner — Jeffrey D Asch*(74) Attorney, Agent, or Firm* — Renner, Otto, Boisselle & Sklar, LLP(57) CLAIM

The ornamental design for a mobile phone, as shown and described.

DESCRIPTION

FIG. 1 is a front view of a mobile phone showing my design in a closed configuration;

FIG. 2 is a rear view thereof;

FIG. 3 is a top view thereof;

FIG. 4 is a bottom view thereof;

FIG. 5 is a left side view thereof;

FIG. 6 is a right side thereof;

FIG. 7 is a perspective view thereof;

FIG. 8 is a front view of the mobile phone in an open configuration;

FIG. 9 is a rear view thereof;

FIG. 10 is a top view thereof;

FIG. 11 is a bottom view thereof;

FIG. 12 is a left side view thereof;

FIG. 13 is a right side thereof; and,

FIG. 14 is a perspective view thereof.

The outermost broken lines shown in FIG. 9 represent the bounds of the claimed design while all other broken lines are directed to environment and are for illustrative purposes only; the broken lines form no part of the claimed design.
